Attorneys.

UNITED STATES PATENT OFFICE.

WALTER EDWARDS, OF KOKOMO, INDIANA.

STOOL AND CHAIR CONSTRUCTION.

Application filed October 19, 1926. Serial No. 142,689.

This invention relates to camp stools, and more particularly camp stools of the folding type, the primary object of the invention being to provide a camp stool wherein the body thereof is constructed of metal, the legs being formed of pivotally connected sections to the end that the stool may be folded into a small and compact article for storing or transporting.

10 Another important object of the invention is to provide novel means whereby the leg sections will be held in their extended positions when the leg sections are moved to their active positions, without the use of 15 clips, latches or the like.

Another object of the invention is to provide a folding chair having a back rest of a novel construction whereby the leg sections of the chair may be folded to a position 20 within the back rest to provide a small and compact article.

A still further object of the invention is to provide a substantially wide metallic cross piece having offset end portions defining 25 pockets to receive the leg sections when the chair is in its folded position.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawing:

Figure 1 is a vertical sectional view illustrating a camp stool constructed in accordance with the invention as extended to its active position.

Figure 2 is an elevational view illustrating the stool in a partially folded position.

45 Figure 3 is an elevational view showing the stool folded.

Figure 4 is a side elevational view taken on line 4-4 of Figure 3.

Referring to the drawing in detail, the 50 stool includes a pair of U-shaped upper leg sections 5 and 6 respectively, the free ends of the section 6 being connected by means of the rod 7 which is secured to the leg sections to move therewith.

55 The leg members of the section 5 are formed with openings adjacent to their outer

ends, which openings accommodate the rod 7 in such a way as to permit of pivotal movement of the section 5 with respect to the rod 7.

Formed integral with the leg members of each section and disposed adjacent to the free ends thereof, are inwardly extended lugs 8 and 9 respectively, which lugs act as stops for the lower pivoted leg sections 65 to be hereinafter more fully described.

The lower pivoted leg sections are indicated by the reference characters 10 and 11 respectively and are also substantially U-shaped, the same being formed of lengths of 70 metal bent to provide leg sections as clearly shown by the drawing. The inner ends of the leg members of the section 11 are formed with openings to accommodate the rod 7 to pivotally connect the section 11 to the rod, the free ends of the leg members of the section 11 being positioned between the leg members of the sections 5 and 6.

Cut out portions are formed in the edges of the leg members of section 11 and receive 80 the lugs 8 of the section 6, when the section 11 is moved to its active position.

The leg members of the section 10 are also provided with openings to accommodate the rod 7 and as shown, these leg members are formed with cut out portions or notches to accommodate the lugs 9 of the section 5 to lock the upper and lower leg sections in their extended positions.

A seat portion indicated at 12 is formed of suitable heavy fabric material and has its ends connected to the upper portions 5 and 6 of the leg members to prevent spreading of the leg section and at the same time act as a seat for the person using the 95 stool.

From the foregoing it will be obvious that due to this construction the pivoted leg sections may be folded one within the other to provide a substantially small and compact 100 article for storing purposes.

The back rest which forms an important feature of the invention embodies an upper section including side members 13 which are connected by means of the substantially 105 wide metallic member 14 which has offset portions 15 formed adjacent to the ends thereof to receive the leg sections when the leg sections are folded, with the result that the leg sections may lie flush with the back 110 rest.

The reference character 16 indicates piv-

oted arms connected to the section 6, the upper ends of the arms having pivotal connection with the side members 13 at 17, the arms 16 being however formed with notches 18 that accommodate the laterally disposed lugs 19 formed at the lower ends of the members 13 to lock the members 13 and arms 16 against pivotal movement, in one direction.

10. Bosses 20 are formed on the sections 6 against which the arms 16 move to hold the arms 16 in their active positions.

From the foregoing it will be obvious that due to this construction, the leg sections 15 may be folded together and the back rest swung forwardly to a position as shown by Figure 3, whereupon the offset portions 15 of the member 14, receive the leg sections to provide a small and compact folded 20 article.

I claim:

1. A chair including pivotally connected leg sections, a seat portion connecting the

upper ends of the leg sections, a back rest pivotally connected with one of the leg sections, a substantially wide back engaging member extending across the back rest and having offset end portions, said offset end portions defining pockets to receive portions of the leg sections when the chair is in its folded position.

2. A chair including pivotally connected leg sections, a fabric seat section connecting the upper ends of the leg sections, a back rest pivotally connected with one of the leg sections, a bracing member forming a part of the back rest, said bracing member having one of its side faces flush with the forward edges of the back rest, and said bracing member having offset portions to receive portions of the leg sections when the chair is in its folded position.

In testimony that I claim the foregoing as my own, I have hereto affixed my signature.

WALTER EDWARDS.
